(57) **CLAIM**

The ornamental design for a terminal, as shown and described.

DESCRIPTION

FIG. 1 is a perspective view of one embodiment of a terminal embodying our new design;

FIG. 2 is a front view thereof;

FIG. 3 is a left side view thereof;

FIG. 4 is a right side view thereof;

FIG. 5 is a perspective view of a second embodiment of a terminal embodying our new design;

FIG. 6 is a front view thereof;

FIG. 7 is a left side view thereof;

FIG. 8 is a right side view thereof;

FIG. 9 is a perspective view of a third embodiment of a terminal embodying our new design;

FIG. 10 is a front view thereof;

FIG. 11 is a left side view thereof; and,

FIG. 12 is a right side view thereof.

The broken lines are for illustrative purposes only and do not form part of the claimed design.
